JAMES N. VANDEGRIFT, OF NEW YORK, N. Y., ASSIGNOR TO INTERNATIONAL BITUMENOIL CORPORATION, OF NEW YORK, N. Y., A CORPORATION OF DELAWARE

RETOUR

Application filed March 24, 1928. Serial No. 264,294.

The object of this invention is to provide a retort for low temperature distillation of bituminous coals, lignites, oil sands, oil shales, and other carbonaceous materials.

5 In a co-pending application of Lars G. Nilson, Serial No. 81,467 filed May 12, 1928, a retort is shown in which bituminous coking coals may be treated successively in a single tube, revolving retort provided with a vapor take-off and the zoning of the heat in separate furnace chambers is maintained. The present invention provides a tubular retort of the revolving type of very simple construction, in which the cylinder is rotated by 10 direct, silent and efficient propelling means. Furthermore, in the present retort the revolving chamber is heated progressively to different temperatures in different parts or zones thereof, without the use of an outer 15 wall or shell on the retort chamber. Instead, in the present retort the heat from the burners is localized, so that different portions of the cylinder may be heated to different temperatures, but the means for applying the 20 heat to the cylinder is stationary and therefore does not need to revolve with the cylinder. In addition, heat equalizing material which it was proposed to use between the 25 double walled cylinders in previous constructions is eliminated in the present case.

Another object of the invention is to provide simple and efficient means for sealing the retort at the intake end to prevent the intake of air or the escape of vapors at the 30 intake end. I also provide simple means for preventing the escape of vapors at the discharge end of the retort and I provide simple means for cooling the coke or lignite char before it discharges from the air seal at the 35 discharge end of the retort.

Other advantages and features will be set forth in the following detailed description of my invention.

40 In the drawings forming part of this application,

Figure 1 is a vertical, longitudinal sectional view of the present invention taken through the center thereof,

45 Figure 2 is an end view thereof with sec-

tion through line 2-2 looking at the left hand end of Figure 1,

Figure 3 is a sectional view taken on the line 3-3 of Figure 1, and

Figure 4 is a sectional view taken on the 55 line 4-4 of Figure 1.

In the drawings I have shown a metal cylinder 7 which is revolvably mounted and which comprises the chamber in which the material to be treated travels and in which it is subjected to heat for the purpose of extracting the volatiles therefrom. This revolvable cylinder is inclined to the horizontal so that the carbonaceous material will progress through it by gravity while under 60 treatment and will be agitated by the turning over of the material. I have shown an annular eye ring 11 attached adjacent the discharge end of the revolving cylinder and this is mounted to turn upon rollers 12 suitably 65 mounted in a base or support 17. Adjacent the opposite end of this cylinder there is a similar annular eye ring 11 which also rests upon the rollers 12 arranged at opposite sides of the vertical center of the revolving cylinder. Instead of using an annular gear and a 70 pinion for revolving the cylinder, the annular eye ring 11 has a smooth exterior and the rollers 12 also have smooth exteriors; and one or more of these trunnions is or are driven to 75 propel the cylinder by rolling contact. This eliminates the noise and vibration which is present whenever a cylinder of this type is driven through a pinion operating on an annular gear on the cylinder. In the present 80 case I have shown a worm gear 14 mounted on the shaft 13 of one of the rollers and this worm gear is operated by means of a worm 85 15 arranged on the shaft of the motor 16. The power of the motor is, therefore, transmitted through the worm 15 to the worm gear 14 and thus to one of the rollers 12; and there is sufficient traction between this and the annular ring 11 to cause the retort cylinder to be revolved.

90 The cylinder 7 is enclosed by a stationary structure, preferably of firebrick, comprising a top wall 30, preferably of arched shape, side walls 50 and a bottom wall or base 31. These walls are of larger 100

interior shape than the enclosed cylinder, so that there is provided below the cylinder the chambers 33, in which combustion takes place, and these chambers are divided off into zones or sections lengthwise of the retort cylinder by means of vertical dividing walls 51, the upper curved edges of which lie adjacent to but not in contact with the outer surface of the cylinder 7. These walls 51 extend upwardly and partly around the cylinder but the space 52 above these walls is continuous, the full length of the cylinder between the laterally extending end wall 52 of one end of the cylinder and the laterally extending wall 53 near the opposite end of the cylinder.

The present device is preferably heated by combustion from oil or gas burners and for this purpose I have shown the burner 36 projecting through one of the side walls 50 at an oblique angle, so that the jet or flame from this burner will be projected downwardly in the fire chamber 33. Interposed between the bottom 31 and the revolving cylinder is a fire wall which will distribute the heat applied to the revolving cylinder, so that the heat is equalized and the same purpose is accomplished as in devices having a double walled cylinder with a heat equalizing material between the walls. In the present case I have shown plates 34 which may be made of carbonium or other refractory material and in the particular form shown herein these plates are arcuate in shape, so that they lie concentric with the revolving cylinder and are spaced therefrom to provide a space 54. These plates may be formed with interlocking edges as shown in the drawings, so that they may be made up in sections for convenient assembly. They rest on the abutments 35 formed in the fire chambers 33 and some of them rest in recesses 38 formed in the vertical dividing walls 51. At one side these plates, as shown at 55, rest against one of the side walls 50 of the enclosing structure, so that the flame projected by the burner 36 into the space between the bottom 31 and the protecting plate, 34 is caused to pass under and around the protecting plate, so that the products of combustion pass partly around the revolving cylinder in direct contact with the protecting plate before coming into direct contact with the revolving cylinder. The opposite edge of the protecting plate is separated from the side wall 51, as shown at 56, so that the products of combustion may at this point pass into the annular space 54 as well as into the space 52 between the upper portion of the revolving cylinder and the arched enclosing top wall 30. The products of combustion in traversing the under side of the protecting plate 34, give up considerable heat to this plate which conducts the heat to the air in the intermediate space 54 which gives up its heat to the revolving cylinder.

By the time these products of combustion pass from the protecting plate at the point 56 and come into direct contact with the outer surface of the cylinder, sufficient heat will have been given up by these products of combustion to permit them to come into direct contact with the cylinder and not scale or otherwise damage the surface of the cylinder.

The products of combustion from the several combustion chambers 33 merge in the space 52 and travel over the upper portion of the cylinder in the opposite direction to the travel of the carbonaceous material in the cylinder, and these products of combustion escape through the flue or chimney 42. The burners 36 are provided for each of the fire chambers 33 but they are so designed that a greater temperature will be created in the chamber 33 adjacent the discharge end of the cylinder and in the next fire chamber a lesser temperature will be maintained, and in the fire chamber 33 at the left in Figure 1, a temperature will be maintained which is lower than that in the other chambers. Regardless of the number of these fire chambers, they will be maintained at progressively different temperatures. This may be accomplished by either having a greater number of burners 36 in the first fire chamber and fewer in the succeeding ones, or burners of larger capacity may be provided in the end chamber 33 and burners of lesser capacity in the succeeding ones.

I provide means in the present case for zoning the heat; that is to say, for permitting different portions of the cylinder to be heated and maintained at relatively different temperatures in order that the material under treatment may be raised in temperature in stages or degrees while traveling through the revolving cylinder. In the present case I have shown an air flue 57 which is formed first in one of the side walls 50 and in each dividing wall 51 and at the other side of the retort this merges with the vertical flue 58 passing upwardly through one of the side walls 50 and discharging at the top of the retort. Any form of air damper 59 may be provided at the intake end of this air flue to regulate the flow of air therethrough. At the point under the center of the cylinder 7 I have shown a metallic plate 60 forming a thin wall between the flue 57 and the annular space 54 surrounding the retort cylinder, to permit rapid conduction of cool air passing through the flue 57 to the cylinder. When the device is in operation, air circulates through the flue 57 which is intermediate each of the several fire chambers 33 and the cooling action of this air prevents the heat from one fire chamber from passing to an adjacent fire chamber and by this means I am able to zone the heat, or, in other words, control its application to the cylinder in such manner that different por-

tions of the cylinder may be maintained at different temperatures.

The carbonaceous material to be treated is introduced into the hopper 1, so that it falls into a tubular device 2 which projects through the end wall or head 9 of the revolving cylinder. There is a screw conveyor 3 arranged in this tubular member for forcing the carbonaceous material through the tubular member to discharge it into the revolving cylinder, but the end of this screw conveyor terminates some distance behind the extreme inner end of the tubular member 2 so that the carbonaceous material will pile up in this tubular member, as shown at 6, beyond the end of the screw conveyor and form a seal which will prevent air from entering within the cylinder and also prevent the escape of the vapors evolved, at this end of the cylinder. This is one of the novel features of the present device. The screw conveyor 3 is mounted upon a shaft 4 which projects through the front wall of the hopper and is provided with a sprocket 5 which may be operated by a chain from any source of power, not shown. The discharge end of the revolving cylinder extends through a circular opening in the wall of a collecting chamber 20 in which the volatiles evolved from the carbonaceous material collect and from which they are discharged by a pipe 21 into a suitable condenser, not shown, or into any other receiving means. The collecting chamber 20 extends downwardly below the level of the cylinder and is shaped to provide a horizontal chamber 61 in which the coke, lignite char or residue material falls as it passes out of the end of the cylinder. Within this discharge chamber I have shown an endless conveyor 22 which travels around spaced pulleys 23 which may be operated by power applied to the shaft of one of these pulleys. The discharge end of the chamber 61 comprises a downwardly directed portion 62 into which the spent material falls from the conveyor 22 and the lower end of this portion is closed by a valve 25 pivoted on a pin and held normally closed by a weight 63 until such time as the weight of the material accumulated on the valve 25 overcomes that of the weight 63 and opens the valve to discharge the spent material.

The discharge chamber 61 is mounted in a tank 27 and the space surrounding the chamber is filled with water 64 or other cooling medium, the water being caused to circulate from an inlet pipe 28 and to flow out through an outlet pipe 29. The water in this tank serves to cool the spent material while it is moving to the discharge opening. By reducing the temperature of the spent material at least to a certain extent, the danger of combustion of the spent material is avoided.

I have shown the usual lifters 8 arranged along the interior of the revolving cylinder 7 the purpose of which is to continually lift the

carbonaceous material and drop it, so that it will be agitated, and all portions will be subjected to the heat transmitted to the cylinder.

In operation the retort cylinder is continually revolved by means of the motor 16 operating through the mechanism described. The carbonaceous material to be treated is fed from the hopper 1 by the screw conveyor 3 into the receiving end of the cylinder, and then the material travels by gravity through the cylinder to the discharge end. The spent material falls onto the conveyor 22 and is conveyed by the latter into the discharge member 62, the material being cooled by the action of the water 64 in the tank 27 before it is discharged into the open air. The vapors evolved from the material collect in the chamber 20 and are conducted off by the pipe 21. When the carbonaceous material enters the receiving end of the cylinder it is heated to a degree which will be slightly below the volatilizing temperature and as it progresses along the retort it is subjected to greater heat so that by the time it arrives near the discharge end of the retort it will have been raised to a temperature which will cause the rapid or almost instantaneous separation of the volatiles. The progressive heating of the material is effected by reason of the progressively higher temperatures produced by the burners in the several compartments 33 and the heat from these several burner compartments will be confined to a great extent within certain zones by reason of the dividing walls 51 and by reason of the air circulating through the flues 57 as required.

I have shown an adjustable packing ring 10 carried by the header 9 of the cylinder which surrounds the feed tube 2 and prevents the escape of vapors or the entry of exterior air at this point. Preferably, the rollers 12 are mounted on antifriction or ball bearings, so that the cylinder may be revolved with the least resistance. The dampers 59 may be regulated to control the flow of cool air through the cross flues 57 in order to prevent the substantial conduction of the heat from one heat zone to another along the retort cylinder. Flames from the burners traveling under the protecting plates 34 have sufficient travel so that they lose enough heat before coming into contact with the retort cylinder, and this prevents the direct flame from striking the cylinder and, therefore, prevents deterioration by scaling.

Having described my invention, what I claim is:

1. A retort including an inclined, revolvable retort cylinder through which the material to be treated travels, means forming an enclosing structure surrounding said cylinder and spaced therefrom, said structure forming a fire compartment under said cylinder, means for dividing said fire compartment

- ment laterally of said cylinder to form a plurality of fire chambers lengthwise of the cylinder, combustion means in said fire chambers and protecting plates arranged between the combustion means and the lower portion of said revolvable cylinder, said plates being spaced from and substantially concentric with said cylinder and arranged to permit the products of combustion to pass into direct contact with the upper portion of said cylinder after traversing the under side of said plates.
2. A retort including an inclined, revolvable retort cylinder through which the material to be treated travels, means forming an enclosing structure surrounding said cylinder and spaced therefrom, said structure forming a compartment under said cylinder, lateral dividing walls for dividing said compartment into a plurality of fire chambers, said dividing walls having flues for the circulation of a cooling medium therein and combustion means in said several fire chambers for heating said revolvable cylinder.
3. A retort including an inclined, revolvable retort cylinder through which the material to be treated travels, means forming an enclosing structure surrounding said cylinder and spaced therefrom, said structure forming a compartment under said cylinder, lateral walls for dividing said compartment into a plurality of separate fire chambers, said dividing walls having flues therein for the circulation of a cooling medium, combustion means in said fire chambers and protecting plates arranged between said combustion means and the lower portion of said revolvable cylinder for preventing the direct contact of the flames with the lower portion of said cylinder.
4. A retort including an inclined, revolvable retort cylinder through which the material to be treated travels, means forming an enclosing structure surrounding said cylinder and spaced therefrom, said structure forming a compartment under said cylinder, lateral walls for dividing said compartment into a plurality of separate fire chambers, said walls having air flues therein, dampers for regulating the circulation of air in said flues, combustion means in said fire chambers, and protecting plates arranged between the combustion means and the lower portion of said revolvable cylinder for preventing the direct contact of the flames with the lower portions of the cylinder.

Signed at the city, county and State of New York, the 20th day of February, 1928.

JAMES N. VANDEGRIFT.
